US00D732472S

(12) **United States Design Patent**
Laffon et al.

(10) **Patent No.:** **US D732,472 S**
(45) **Date of Patent:** **** Jun. 23, 2015**

(54) **POWER ADAPTER**

(75) Inventors: **Emmanuel Laffon**, Burlingame, CA (US); **Marc Walliser**, San Francisco, CA (US); **Christopher Green**, San Francisco, CA (US)

(73) Assignee: **Amazon Technologies, Inc.**, Reno, NV (US)

(**) Term: **14 Years**

(21) Appl. No.: **29/430,011**

(22) Filed: **Aug. 20, 2012**

(51) LOC (10) Cl. **13-02**

(52) U.S. Cl.

USPC **D13/110**

(58) **Field of Classification Search**

USPC D13/110, 103, 107, 108, 118, 119, D13/138.1, 138.2, 139.1, 139.2, 184, 199; D14/253, 432, 433, 434; 320/107-115; 439/103, 104, 105, 131, 172

See application file for complete search history.

Primary Examiner — Derrick Holland

(74) *Attorney, Agent, or Firm* — Lee & Hayes, PLLC

(57) **CLAIM**

The ornamental design for a power adapter, as shown and described.

DESCRIPTION

FIG. 1 is a perspective view of a power adapter; FIG. 2 is another perspective view of the power adapter of FIG. 1;

FIG. 3 is a bottom plan view of the power adapter of FIG. 1; FIG. 4 is a front elevation view of the power adapter of FIG. 1;

FIG. 5 is a right-side elevation view of the power adapter of FIG. 1, the left-side elevation view of the power adapter of FIG. 1 being a mirror image of FIG. 5;

FIG. 6 is a back elevation view of the power adapter of FIG. 1; and,

FIG. 7 is a top plan view of the power adapter of FIG. 1. The broken lines are directed to unclaimed portions and form no part of the claimed design.

1 Claim, 2 Drawing Sheets
